UNITED STATES PATENT OFFICE.

WILLIAM A. READE, OF CLEVELAND, OHIO, ASSIGNOR TO THE LUDLOW TYPOGRAPH COMPANY, OF CLEVELAND, OHIO, A CORPORATION OF MAINE.

TYPOGRAPH-MACHINE.

1,266,156.

Specification of Letters Patent.

Patented May 14, 1918.

Application filed June 19, 1915. Serial No. 35,070.

To all whom it may concern:

Be it known that I, WILLIAM A. READE, a citizen of the United States, and a resident of Cleveland, county of Cuyahoga, and State of Ohio, have invented a new and useful Improvement in Typograph-Machines, of which the following is a specification, the principle of the invention being herein explained and the best mode in which I have 10 contemplated applying that principle, so as to distinguish it from other inventions.

As is well known, larger type than can be formed from the matrix bars regularly used on typographs are very frequently desired 15 for printing head lines and advertisements. To set up matter containing characters of this sort it has heretofore been necessary to use the same large type which are regularly employed by printers, and if much such 20 work requires to be done, it is obviously necessary to maintain a large stock of "sorts". The object of the present invention is to provide a typograph mechanism whereby slugs or type bars may be cast in any number from 25 a single font of matrices of such larger type.

To the accomplishment of the foregoing and related ends said invention, then, consists of the means hereinafter fully described and particularly pointed out in the claims, 30 it being noted that the present invention is in the nature of an improvement on the typograph mechanism which forms the subject matter of my co-pending application filed May 22, 1911, Serial No. 628,649. In

35 other words, like the typograph machine in the aforesaid application, the present mechanism involves the use, in combination with suitable slug-casting mechanism, of a set or font of detached matrix bars and an independent member arranged to receive and hold a number of said bars in selected relation, thereby forming a composite matrix apart from, but adapted to coöperate with, 40 said casting mechanism.

45 The annexed drawings and the following description set forth in detail certain mechanism embodying the invention, such disclosed means constituting, however, but one of various mechanical forms in which the 50 principle of the invention may be used.

In said annexed drawings:—

Figure 1 is a front elevation of my improved typograph mechanism; Fig. 2 is an elevation of the same as viewed from the right in Fig. 1; Fig. 3 is a front elevation

similar to Fig. 1, but showing the parts in a different operative position; Fig. 4 is a plan view of the mechanism; Fig. 5 is a plan view of one of the elements or component parts of such mechanism consisting of a holder for 60 the detached matrices or matrix bars; Fig. 6 is a side elevation of such holder by itself; Fig. 7 is a perspective view of two of the detached matrices or matrix bars designed for use in the mechanism in conjunction with 65 such holder; Fig. 8 is a vertical section of the mechanism with the parts in one operative position, the plane of the section being indicated by the broken line 8—8, Fig. 4; Fig. 9 is a section similar to that in Fig. 8, 70 but showing the parts in a subsequent operative position; Fig. 10 is a similar sectional view showing the parts in a still later operative position; and Fig. 11 is a perspective view of a slug or type-bar made by 75 my improved mechanism.

The general features of construction of the casting mechanism, forming a part of the present improved typograph, are the same as those shown and described in United States Letters Patent No. 1,124,293 to E. S. Carman, for casting mechanism for typographs, granted January 12, 1915, the parts of present interest comprising a mold 1 supported so as to be capable of vertical movement from the casting position shown in 80 Figs. 1, 3 and 8 to the slug ejecting position shown in Fig. 10 and back again to such casting position.

Coöoperative with such mold in the latter's 90 casting position, is a casting pot of which only the nozzle 2 is shown, such pot being supported so as to permit the nozzle to be moved entirely out of the path of movement of the mold just described, and including 95 suitable means (not shown), whereby the molten metal may be forced into the casting slot 4 in the mold when the latter is in proper position, as will be readily understood. The end of the nozzle is provided 100 with a squirt plate 3 of usual construction, which comes into direct contact with the under side of the mold, the slot in the latter being of such form and dimensions as to serve as a mold for a slug body of the desired length and width.

In its casting position the mold registers with, or rather lies in, an opening 5 in the horizontally extending top 6 of the general machine frame, so as to be substantially 110

flush with the upper surface of such top, or rather with the surface of a trough-like depression 7 extending transversely across the same from the front to the rear as shown in Fig. 4. Associated with the mold so as to be carried therewith in its vertical movement, is a trimming knife or blade 8 in the form of a slide, such slideable trimmer blade being retracted in the casting position of the mold, as shown in Fig. 8, and being capable of being thereupon advanced across the casting slot in such mold, after the nozzle of the casting pot has been withdrawn. The sequence of operations, to which some importance is attached, will be subsequently set forth in describing the general operation of the mechanism.

The extent and form of the table top 6 are more or less a matter of indifference, such top primarily forming a support for the matrix holder, pending the placing of the same over the mold, and the withdrawal of the latter therefrom when the slug has been cast. Preferably, however, said top is relatively extensive and closed instead of being merely an open frame work, such as might otherwise suffice, in order better to protect the operator and the parts of the machine supported on the top, from the heat and gases arising from the casting pot.

Disposed alongside the trough or depression 7 in the top, designed to receive the matrix holders, as already set forth, is a guide 9 that extends substantially to the opening 5 wherewith the mold registers in its casting position. Adjacent one side of such opening is a stop block 10 adjustably fixed to the table by means of set screws 11 and clamp screws 12 as will be readily understood; while adjacent the opposite side of the opening is a presser foot 13, movably held in the forward end of a slide 14, a compression spring 15 being interposed between such foot and slide so as to afford a resilient backing for the former. Oscillatorily mounted upon said slide about a transverse pivot 16, is a lever 17, the forward end of which projects over the opening 5 in the table and carries a bar 18, alined with such opening, said bar being pivotally secured to the front end of said lever by a pin 19 so as to be adapted to press uniformly on the backs of the assembled matrices in the holder, as will be presently explained. To further assist in thus securing uniform contact with such matrices, the under side of this clamp bar is rounded off transversely, as shown in Figs. 1 and 3.

A handled lever 20, pivotally mounted on the top 6 about an axis 21 transverse to the direction of movement of the slide 14, is connected with the latter by means of a link 22 so that said slide, with the presser foot 13 will be moved forwardly, that is to the right, as shown in Fig. 1, when said handled

lever is depressed. The forward end of link 22 projects beneath the rear end of the lever 17 that carries clamp bar 18, a set-screw 23 in such lever-end contacting with such projecting portion when the link is oscillated incidentally to the depression of the hand lever, the effect of such engagement being obviously to depress the clamp bar. A flat leaf-spring 24 under the forward end of the lever 17 normally holds such clamp bar in in-operative position, while a compression spring 25 is similarly provided to normally raise the handled lever 20 and thus retract the slide and presser foot carried thereby.

In this condition of parts the matrix holder 26, shown in plan and side elevation in Figs. 5 and 6 respectively, is adapted to be inserted between the fixed stop 10 and such presser foot, such holder being conveniently moved along the trough or depression 7 in the table top in engagement with the guide 9 into such desired position. The exact longitudinal location of the holder is determined by means of a stop block 27 that projects over such trough so as to engage the rear end of the holder when it is thus moved, being adjustably secured to the top by means of screws 28.

As shown in the figures last referred to, the holder in its preferred structural form, comprises two end pieces 29 secured to side members 30 of sufficient length to provide an opening somewhat larger than the maximum length of the slug which it is desired to cast, as for example sixteen ems in the case of a fifteen em slug. Slidably mounted between the side members 30 at one end of the holder is a clamp member, or block 31, that is engaged by the threaded portion 105 of a screw 32 rotatably secured in the adjacent end piece 29 and provided with a knurled head, by rotating which said block can obviously be advanced or retracted to clamp the assembled matrices, or matrix bars 33, as they may be termed to distinguish them from the impressions 34 of the type characters, which constitute the matrices proper.

These bars are of the general form illustrated in Fig. 7, being in effect plates or blocks of uniform length and height but of varying width to accommodate character impressions of correspondingly varying width. The latter are struck or driven in the bottoms of recesses cut in what may be called the lower edges of the bars, these recesses comprising a portion 35 having a width and depth prescribed by the dimensions which it is desired the head of the slug 36 (Fig. 11) should have, it being understood that the depth of such head, plus the depth of the body portion of the slug, should equal the height of ordinary slugs as commercially made, so that both kinds of slugs can be 130

used in the same form, if desired. In addition to the main recess portion 35, a supplemental recess 37 is formed, where the character is of less extent than such main recess, 5 to receive the character impression 34, the object being to have the molded character 38 formed by the matrix on the slug on an entablature 39 of as limited extent as possible in order to prevent smearing of the 10 printed sheet by ink carried on the blank face of the slug.

The upper portions of the matrices project laterally in the form of ears 40 which are adapted to rest on the side pieces 30 of the 15 holder, leaving the bodies of the matrices depend between and some distance below such side pieces, as shown in Fig. 8, for example. In order to facilitate the insertion of the matrices in the holder, the inner faces 20 of such side pieces are slightly beveled or flared upwardly, a close fit being secured, however, between their lower edges and the matrix bars, so as to insure the correct alignment of the latter in a horizontal plane. The 25 extent of the assembled line of matrices can be readily determined by graduations 41 on the upper face of one side piece of the holder, and if necessary the line may be filled out, as well as proper spaces provided, 30 by the insertion of blank matrix bars, as will be readily understood. When a line of proper length has been assembled, the matrix bars are clamped longitudinally of the holder by turning the screw 32, and the 35 holder may then be placed on the table over the opening 5, as previously explained, the mold being shown in casting position in Fig. 1. Thereupon said holder is clamped securely in place by actuating handled lever 40 20 which simultaneously forces the presser foot 13 against the side of the holder and depresses the clamp bar 18 into engagement with the backs or upper edges of the matrix bars 33. The effect of this clamp bar is to 45 forcefully press the matrices against the upper face of the mold 1, thus insuring the accurate alignment of such matrices in a vertical plane. In other words, it is not necessary to accurately gage the location of the 50 ears 40 on the matrix bars in order to accomplish this result, since the only purpose of such ears is to prevent the bars from dropping through the opening in the holder, such holder laterally encompassing the bars 55 merely.

Having thus described the construction of the various component parts of my improved typograph mechanism, the mode of operation of the same as a whole may be 60 briefly set forth.

A body of matrix bars 38 having been selected, placed and clamped in the holder to form a line of the desired length, a composite matrix is obviously formed by the 65 assemblage of the individual matrices 34 in

the bottoms of the recesses 35 of such bars. This composite matrix is accurately aligned with respect to the casting slot 4 in the mold 1 by the several locating devices on the top 70 of the machine, and the body of matrices thereupon forced downwardly toward the face of the mold by actuation of the handled lever 20. The position of the parts illustrated in Fig. 3 corresponds with this stage of the operation, save that the mold does not yet contact with the bottoms of the matrix bars. The mold is, however, immediately raised to accomplish this result, forcefully 75 clamping the bars against the bar 18. In this situation the matrix bars are, in effect, 80 held firmly between such bar and mold quite independently of the holder or other parts of the mechanism, accurate vertical alignment being thus positively insured despite any slight irregularities in the ears 40 in said 85 matrix bars.

Thereupon, the casting pot is moved to bring the nozzle or spout 2, or rather the squirt plate 3 on such spout, into contact with the under side of the mold, and the 90 metal is forced into the slot in such mold filling the same and the recesses in the assembled matrix bars. This metal quickly sets so that the spout can be immediately moved out of the way. 95

The bottom trimmer blade 8 is next advanced across the under face of the mold so as to cut away or trim off any superfluous metal that may project below such face. As shown in Fig. 9, this trimming operation is 100 performed before the mold is lowered and while the matrices are still held securely clamped against such mold. Absolute accuracy in the sizing of the slug is thus secured, for if the matrices were relieved of the 105 clamping pressure before the blade is advanced there would be a tendency for the slug to be forced upwardly, and it has also been found that in lowering the mold away from the matrices the head of the lug tends 110 to stick in the latter and thus at least slightly to dislodge or loosen the slug so that the trimming will be inaccurate. The mold accordingly is only lowered after the completion of the trimming operation, and thereupon the finished slug 36 is ejected by means (not shown) into the position shown in dotted outline in Fig. 10, thence to be removed in any suitable fashion. The clamp bar being at the same time raised, the matrix 120 holder may be removed and another one with a fresh assemblage of matrix bars substituted in its place. 115

Of course if it is desired to cast a series of similar slugs the same matrix holder may 125 remain clamped in place throughout a series of casting operations, each of which produces a slug. It will be understood, also, that while the present improved mechanism is expected to find its largest and most im- 130

portant field of use in the casting of slugs
56 of the kind illustrated and described, having
enlarged heads so as to carry large characters
5 of the kind used in display work, various
features about the mechanism are adapted
for use in casting slugs of the ordinary
kind, it only being necessary to substitute
matrix bars with the smaller or ordinary
matrix characters for those having
10 such larger characters.

In referring to the matrix bars hereinbefore, as well as in the following claims it will be understood that I use this term to apply to any of the bars in question, irrespective of the character-impression formed thereon. For that matter certain of such bars, as in the ordinary font of type, will be simple blank bars such as are used for spacing, without any character-impressions whatever, being formed on the edge designed to cooperate with the mold.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a typograph machine, the combination with a set of detached matrix bars each having an edge adapted to cooperate with a mold; of a member formed with an elongated opening adapted to receive a number of said bars and support the same in selected relation with both their mold-cooperative edges and the edges opposite thereto exposed, said bars being movable in said member transversely of such edges and in a line normal thereto.

2. In a typograph machine, the combination with a set of detached matrix bars each having an edge adapted to cooperate with a mold; of a member formed with an elongated opening adapted to receive a number of said bars in selected relation, said member having its sides formed to engage with the ends of said bars so as to support the latter with both their mold-cooperative edges and the edges opposite thereto exposed, said bars being movable in said member transversely of such edges and in a line normal thereto.

3. In a typograph machine, the combination with a set of detached matrix bars each having an edge adapted to cooperate with a mold; of a member formed with an elongated opening adapted to receive a number of said bars and support the same in selected relation with both their mold-cooperative edges and the edges opposite thereto exposed, such mold-cooperative edges of said bars lying below the corresponding face of said member when thus supported

therein and said bars being movable in said member transversely of such edges.

4. In a typograph machine, the combination with a set of detached matrix bars each having an edge adapted to cooperate with a mold and oppositely extending lateral projections; of a member formed with an elongated opening adapted to receive a number of said bars and support the same in selected relation with such projections resting on the sides of said member, said bars being movable in said member to raise such projections from such resting position.

5. In a typograph machine, the combination with a set of detached matrix bars each having an edge adapted to cooperate with a mold and oppositely extending lateral projections; of a member formed with an elongated opening adapted to receive a number of said bars and support the same in selected relation with such projections resting on the sides of said member, the mold-cooperative edges of said bars lying below the under face of said member when thus supported therein; said bars being movable in said member transversely of such face to raise such projections from such resting position.

6. In a typograph machine, the combination with a set of detached matrix bars each having an edge adapted to cooperate with a mold and oppositely extending lateral projections; of a member formed with an elongated opening adapted to receive a number of said bars and support the same in selected relation with such projections resting on the sides of said member, the inner faces of such sides flaring upwardly and said bars being movable in said member to raise such projections from such resting position.

7. In a typograph machine, the combination with a set of detached matrix bars each having an edge adapted to cooperate with a mold and oppositely extending lateral projections; of a member formed with an elongated opening adapted to receive a number of said bars and support the same in selected relation with such projections resting on the sides of said member, the inner faces of such sides flaring upwardly and the lower edges of said bars lying below the under face of said holder when thus supported on said sides, said bars being movable in said member transversely of such face to raise such projections from such resting position.

8. In a typograph machine, the combination with a set of detached matrix bars each having an edge adapted to cooperate with a mold and oppositely extending lateral projections; of a member formed with an elongated opening adapted to receive a number of said bars and support the same in selected relation with the lateral projections thereon resting on the sides of said member, said bars being movable in said member to

raise such projections from such resting position; and an adjustable block at one end of the opening in said member adapted to clamp said bars together longitudinally of 5 such opening.

9. In a typograph machine, the combination with a set of detached matrix-bars each having an edge adapted to coöperate with a mold and oppositely extending lateral projections; of a member formed with an elongated opening adapted to receive a number of said bars and support the same in selected relation with the lateral projections thereon resting on the sides of said member, 10 the inner faces of such sides flaring upwardly but closely fitting said bars at the bottom; and an adjustable block at one end of the opening in said member adapted to clamp said bars together longitudinally of 15 such opening.

10. In a typograph machine, the combination of a slug-casting mechanism including a mold formed with a casting slot; a set of detached matrix-bars each having an edge 20 adapted to coöperate with said mold; a member formed with an elongated opening adapted to receive and support a number of said bars in selected relation, thereby forming a composite matrix apart from, but 25 adapted to coöperate with, said mold, said bars being movable in said member transversely of their mold-coöperating edges; and means adapted to directly press upon the bars thus held in said member to clamp 30 the same against said mold.

11. In a typograph machine, the combination of a slug-casting mechanism including a mold formed with a casting slot; a set of detached matrix-bars each having an edge 40 adapted to coöperate with said mold; a member formed with an elongated opening adapted to receive a number of said bars in selected relation and thereby form a composite matrix apart from, but adapted to coöperate with, 45 said mold, said member having its sides formed to engage with the ends of said bars so as to support the latter with both their mold-coöperative edges and the edges opposite thereto exposed, said bars being movable in 50 said member transversely of such edges; and means adapted to directly press upon such opposite edges of the bars thus held in said member to clamp the same against said mold.

12. In a typograph machine, the combination of a slug-casting mechanism including a mold formed with a casting slot; a set of detached matrix-bars each having an edge adapted to coöperate with said mold; 60 a member formed with an elongated opening adapted to receive and support a number of said bars in selected relation, thereby forming a composite matrix apart from, but adapted to coöperate with, said mold; and means adapted to directly press upon 65

the bars thus held in said member to clamp the same against said mold, said means including a depressible bar disposed parallel with said member and oscillatory about a transverse axis so as to press uniformly on all said matrix-bars.

13. In a typograph machine, the combination of a slug-casting mechanism including a mold formed with a casting slot; a set of detached matrix-bars each having an edge 70 adapted to coöperate with said mold; a member formed with an elongated opening adapted to receive and support a number of said bars in selected relation, thereby forming a composite matrix apart from, but 75 adapted to coöperate with, said mold; and means adapted to directly press upon the bars thus held in said member to clamp the same against said mold, said means including a depressible bar disposed parallel with said member and having its lower edge 80 transversely rounded, said member being oscillatory about a transverse axis so as to press uniformly on all said matrix bars.

14. In a typograph machine, the combination of a slug-casting mechanism including a mold formed with a casting slot; a set of detached matrix-bars each having an edge 85 adapted to coöperate with a mold and oppositely extending lateral projections; a member formed with an elongated opening adapted to receive a number of said bars and support the same in selected relation with such projections resting on the sides 90 of said member, thereby forming a composite matrix apart from, but adapted to coöperate with, said mold, the lower faces 95 of said bars lying below the under face of said member when thus supported therein, and said bars being movable in said member transversely of such faces to raise such 100 projections from such resting position; and means adapted to directly press upon the upper edges of the bars thus held in said member to clamp the same against said 105 mold.

15. In a typograph machine, the combination of a slug-casting mechanism including a mold formed with a casting slot; a set of detached matrix-bars each having an edge 110 adapted to coöperate with a mold; a member formed with an elongated opening adapted to receive and support a number of said bars in selected relation, thereby forming a composite matrix apart from, but 115 adapted to coöperate with said mold, said bars being movable in said member transversely of their mold-coöperating edges; means adapted to secure said member with such composite matrix properly aligned with 120 the slot in said mold; and means adapted to directly press upon the bars thus held in said member to clamp the same against said mold.

16. In a typograph machine, the combina- 125

- tion of a slug-casting mechanism including a mold formed with a casting slot; a set of detached matrix-bars each having an edge adapted to coöperate with a mold; a member formed with an elongated opening adapted to receive and support a number of said bars in selected relation, thereby forming a composite matrix apart from, but adapted to coöperate with, said mold; a stop block adapted to locate said member with such composite matrix properly alined with the slot in said mold; and clamp means adapted to secure said member in such location.
17. In a typograph machine, the combination of a slug-casting mechanism including a mold formed with a casting slot; a set of detached matrix-bars each having an edge adapted to coöperate with a mold; a member formed with an elongated opening adapted to receive and support a number of said bars in selected relation, thereby forming a composite matrix apart from, but adapted to coöperate with, said mold; a stop block adapted to engage one side of said member and thereby locate the same with such composite matrix properly alined with the slot in said mold; and a movable presser-foot adapted to engage the other side of said member to clamp the same against said block.
18. In a typograph machine, the combination of a slug-casting mechanism including a mold formed with a casting slot; a set of detached matrix-bars each having an edge adapted to coöperate with a mold; a member formed with an elongated opening adapted to receive and support a number of said bars in selected relation, thereby forming a composite matrix apart from, but adapted to coöperate with, said mold; a stop block adapted to locate said member with such composite matrix properly alined with the slot in said mold; clamp means adapted to secure said member in such location; and means adapted to directly press upon the upper edges of the bars held in said member to clamp the same against said mold.
19. In a typograph machine, the combina-
- tion of a slug-casting mechanism including a mold formed with a casting slot; a set of detached matrix-bars each having an edge adapted to coöperate with a mold; a member formed with an elongated opening adapted to receive and support a number of said bars in selected relation, thereby forming a composite matrix apart from, but adapted to coöperate with, said mold; a stop block adapted to locate said member with such composite matrix properly alined with the slot in said mold; clamp means adapted to secure said member in such location; and means adapted to directly press upon the upper edges of the bars held in said member to clamp the same against said mold, said two last-named means being conjointly operable.
20. In a typograph machine, the combination of a slug-casting mechanism including a mold formed with a casting slot; a set of detached matrix-bars each having an edge adapted to coöperate with a mold; a member formed with an elongated opening adapted to receive and support a number of said bars in selected relation, thereby forming a composite matrix apart from, but adapted to coöperate with, said mold; a stop block adapted to engage one side of said member and thereby locate the same with such composite matrix properly alined with the slot in said mold; a movable presser-foot adapted to engage the other side of said member to clamp the same against said block; means adapted to directly press upon the bars held in said member to clamp the same against said mold, said means including a depressible bar disposed parallel with said member and oscillatory about a transverse axis so as to press uniformly on all said matrix-bars; and means adapted conjointly to operate said presser-foot and depressible bar.

Signed by me, this 18th day of June, 1915

WILLIAM A. READE.
